MECHANISM FOR THE INTERMITTENT DRIVING OF CINEMATOGRAPHIC FILMS

Jean Thévenaz, Yverdon, Switzerland, assignor to Paillard S. A., Sainte-Croix, Switzerland, a corporation of Switzerland

Application March 14, 1950, Serial No. 149,502
In Switzerland March 24, 1949

2 Claims. (Cl. 88—18.4)

1

Mechanisms for the intermittent movement of a cinematographic film are known, which are provided with a lever oscillating in a plane perpendicular to the plane of translation of the film and to the end of which is hinged an arm fitted with a claw which, periodically, enters the perforations of the film, moves this through the height of an image and is disengaged therefrom for recommencing its operative cycle. The movements of the claw and those of the oscillating lever may be each controlled by a cam.

In some of these known mechanisms, particularly when the oscillating lever and the claw carrying arm move in separate planes, the claw is liable to vibrate laterally and move away from its plane of action, which gives rise to a deleterious lateral component in the moving force of the film, to irregular wear of the perforations and a lack of fixity.

Further, the return of the oscillating lever, and of the arm carrying the claw against their respective cam is ensured in general by one or more helicoidal traction springs necessarily powerful so that their natural period of vibration is short relatively to the duration of return. Consequently they have a considerable mass which increases the shocks and friction in the mechanism.

The present invention, which has for its object to remedy the disadvantages referred to above, relates to a mechanism for the intermittent movement of a cinematographic film provided with an oscillating claw actuated by a control member and co-operating with the perforations of the film, for producing the movement of the film.

This mechanism is distinguished from known devices by the fact that the said oscillating claw is held in contact with the member controlling the movement of the film by a couple of forces distributed on opposite sides of its axis of oscillation.

In the accompanying drawing, given by way of example,

Fig. 1 shows in a diagrammatic manner, a form of construction of the mechanism seen in inclined perspective.

Fig. 2 is a view in section on the line II—II of Fig. 3.

Fig. 3 is a view in longitudinal section on the line III—III of Fig. 2.

Figs. 4 and 5 are views of details to a larger scale.

In these figures, D and G indicate the uprights of a stationary framework, each provided with a bearing 1, 2 in which turns a shaft 3, set in continuous rotation by a motor not shown. The shaft 3 carries two identical driving cams 4 and 5 in contact with a shoe 6 secured to an oscillating lever 7 of which the oscillation shaft 8 is secured to the upright G.

2

At the free end of the oscillating lever is hinged an arm 9 carrying a double claw 10 provided for penetrating two successive perforations of the film F. The feeding cams 4 and 5, practically identical, are secured co-axially to the shaft 3 in the same angular position. These cams are spaced from one another to provide between them a groove 11 with edges parallel to the plane of oscillation of the claw-carrying arm 9.

This groove constitutes a guide for the said arm 9, which prevents it from moving from its plane of operation. The two driving cams 4 and 5 are held spaced apart by a spacer 12 of a thickness at least equal to that of the arm 9 and which constitutes a penetration cam actuating the arm 9.

According to the arrangement shown in Fig. 3, the two driving cams 4 and 5, made thick in order to reduce the specific pressure of contact on the shoe 6, and the thinner spacer forming the penetrating cam 12 are mounted on a section 13 of the cam shaft 3 and locked against a shoulder 14 of this shaft by a nut 15. An extension 16 of the shaft 3 serves as a trunnion and turns in the bearing 2 provided in the upright G of the framework.

The shoe 6 is held in contact with the driving cams 4 and 5, by a torsion spring 17 of which the axis is located along an extension of the pivotal axis 8 of the oscillating lever 7. The torsion spring is formed by a spring blade located perpendicularly to the plane of oscillation of the lever 7, and of which one end is secured in a cylindrical boss 18 located in a bore 19 of the upright from which it projects. The boss 18 is locked in angular position by a screw 20 engaging with a screw threaded hole of the upright D. Radial recesses 21 provided in the periphery of the boss 18 and into which may be introduced the end of a tool or of a rod, permit of selecting and fixing the angular position of the boss 18 and, consequently, of selecting and fixing the torsion and thus the initial tension of the spring 17. The end of the blade 17 remote from the boss 18, acts on the oscillating lever 7. For this purpose, it has an arcuate slope 22 above the end of the axis of oscillation 8 and forming a fork of which one limb 23 acts on a contact arm 24, and the other 25, on a contact projection 26 diametrically opposite the arm 24 and also secured to the oscillating lever 7. During the mounting, the boss 18 is locked, in a position, such that the branches 23 and 25 of the spring 17 apply to the oscillating lever 7 two equal and opposite forces forming a couple centred on the axis of oscillation 8 and which tends to hold the lever 7 in contact with the profile of the cams 4 and 5.

A torsion spring of any type, but particularly a blade spring operating under torsion, such as above described, permits of obtaining relatively

to known devices, a number of important advantages by means of a single spring:

1. As the couple of forces is centred on the pivotal axis of the oscillating lever 7, the return couple is without direct effect on the wear of the hinge of the oscillating lever.

2. Relatively to an ordinary traction spring for example, having an equal return couple, attached necessarily to a long arm of the lever in order to reduce as far as possible its reaction on the pivotal axis, the torsion spring has a weaker inertia, whilst retaining a superior natural period of vibration. It thus follows that the return is more rapid and that the risks of resonance effects are practically non-existent.

Underneath the range of the contact, the oscillating lever 7 is provided with a bent tongue 27 against which bears, by one of its ends, a resilient blade 28 held flexed by a finger 29. The other end 30 of this resilient blade acts on a beak 31 secured to the arm 9 of the claw 10. By resilient flexing, the end 30 applies to the beak 31 a force which is eccentric relatively to the hinging axis 32 connecting the arm 9 and the oscillating lever 7. This return force causes the arm 9 to bear constantly against the penetration cam 12.

On examination of the accompanying drawing, it will be seen that the oscillating lever 7 and the arm 9 of the claw have a common plane of symmetry, which is the plane of oscillation of the oscillating lever 7. Consequently the forces and reactions acting on the members of the mechanism described are also located in this same plane, which contains the return couple generated by the torsion spring 17.

It thus follows that all the parts and members of the device may be lightened in weight relatively to the parts and members of known devices.

The oscillating lever 7 is secured by rivets 33 on the peripheral flange 34 of an anti-friction sleeve 35 turning freely on the axis of rotation 8 fitted with its reinforced part 36 in the upright G of the framework. A cap 37 screwed into the shaft 8, holds the sleeve 35 on the said shaft.

The profile of the feed cams 4 and 5 is preferably so determined (Fig. 2) that the speeds communicated to the oscillating lever 7 and, consequently to the arm 9 of the claw 10 vary progressively and that the oscillations of the oscillating lever are separated by stopping periods. The penetrating cam 12 acts directly on a projection of the dorsal contact 38 of the arm of the claw of which the movements of penetration into the perforations of the film F and of the disengagement from these, are accomplished preferably approximately at the moment at which the oscillating lever 7 reverses its direction of movement. Further, the portion of the profile of the cam 12 which is in contact with the projection 38 whilst the descending movement of the oscillating lever 7 for driving the film F is preferably so provided as to compensate the effect of the arc of circle described by the hinge axis 32 and to act in such a manner that the claws 10 describe a practically straight line path.

As regards the transmission of forces it is to be observed that at each descending stroke of the oscillating lever 7, the film opposes a resistance to its movement, so that the arm 9 of the claw is subjected to a traction force which is converted into a variable force of application of the oscillating lever, or more particularly of the

shoe 6 against the driving cams 4 and 5. In other words, these cams apply the variable force necessary for moving the film, whilst the torsion spring 17 only supplies the very weak force necessary for holding the lever 7 and its shoe 6 in contact with the cams 4 and 5 and for the idle return of the claw 10, disengaged from the perforations of the film, between two successive feeding strokes.

A form of construction of the mechanism forming the subject of the invention has been described herein by way of example and with reference to the accompanying diagrammatic drawing, but it will be understood that various modalities and variations in construction may be effected without departing from the scope of protection claimed.

In a modification of the form of construction described and shown herein, one only of the branches 23, 25 of the spring 17 may act on the oscillating lever. However, in this case, in order that the spring applies to the oscillating lever a couple of forces distributed on opposite sides of the axis of oscillation of the latter, it is necessary for this single branch to be set in a groove of the lever 7 or secured in other manner thereon.

While the present application claims the combination of the claw arm, the actuating lever therefor and the spring structure urging both elements, applicant's related copending application Serial No. 149,503, filed March 14, 1950, claims the combination of the cam structure, the claw arm and actuating lever.

I claim:

1. A mechanism for intermittently moving a film having perforations therein, comprising, a frame, an arm carrying adjacent one end claw means for insertion in the perforations, a control lever pivoted to the other end of the arm and fulcrumed on the frame, and torsion spring means urging the lever against a cam, said spring means constituted by an elastic blade subjected to torsion and having one of its opposite ends fixed to the frame, the other end of said blade being secured to the lever at two distinct points symmetrically situated with respect to the fulcrum of the lever.

2. A mechanism for intermittently moving a film having perforations therein, comprising, a frame, an arm carrying adjacent one end claw means for insertion in the perforations, a control lever pivoted to the other end of the arm and fulcrumed on the frame, torsion spring means in the form of an elastic blade urging the lever against a cam and having one of its ends secured to the lever at two distinct points symmetrically situated with respect to the fulcrum of the lever, the torsion axis of the spring means coinciding with the fulcrum of the lever, and a boss adjustably mounted in the frame and anchoring the other end of the elastic blade opposite the lever to the frame.
